UNITED STATES PATENT OFFICE.

JOSEPH D. GALLAGHER, OF GLEN RIDGE, NEW JERSEY, ASSIGNOR TO AMERICAN BRAKE SHOE & FOUNDRY COMPANY, OF JERSEY CITY, NEW JERSEY, A CORPORATION OF NEW JERSEY.

BRAKE-SHOE.

No. 907,773.

Specification of Letters Patent.

Patented Dec. 29, 1908.

Application filed January 25, 1907, Serial No. 353,938. Renewed April 28, 1908. Serial No. 429,634.

To all whom it may concern:

Be it known that I, JOSEPH D. GALLAGHER, a citizen of the United States, and a resident of Glen Ridge, in the county of Essex and 5 State of New Jersey, have made and invented certain new and useful Improvements in Brake-Shoes, of which the following is a specification.

My invention relates to an improvement in 10 brake shoes, and more particularly to a reinforcing back therefor, the object being to provide means whereby all portions of the shoe will be tied or bound together, and prevent the separation of the parts in case of 15 fracture during the handling or transportation thereof.

A further object is to provide a reinforcement, located at or adjacent to the back of the shoe, which shall be simple, strong, and 20 capable of performing the functions for which it is intended, without materially adding to the cost of the shoe, and with these and other ends in view, consists in certain novel features of construction, as will be herein- 25 after fully described and pointed out in the claims.

In the accompanying drawings, Figure 1 is a plan view of a brake shoe constructed in accordance with my invention. Fig. 2 is a 30 sectional view taken on the line 2—2 of Fig. 1. Fig. 3 is a perspective view of the reinforcing back. Figs. 4, 5, 6, 7, 8 and 9 are plan views of modified forms of the reinforcing back.

35 By reference to the drawings, it will be seen that in all instances the reinforcing back, made preferably of a single rod, bent or twisted into any of the forms shown, extends over such parts or portions of the back 40 of the shoe as to prevent the separation of the parts should the shoe be cracked or broken, either laterally or lengthwise, the rod crossing and re-crossing the back of the shoe in several directions.

45 In Figs. 1, 2 and 3 I have shown the rod bent or twisted to form several loops A, extending longitudinally of the shoe and located at or adjacent to the back thereof, said loops being curved in the direction of their

length to conform to the curvature of the 50 shoe, a sufficient number of such loops being formed to extend entirely across the shoe. Furthermore, the two loops B, which are formed at about the middle of the reinforcing back, are bent upwardly, forming an integral 55 key-lug, the extreme ends C, D, of the rod lying at the opposite ends of the shoe, and a single length or strand E of the reinforcing back, lying longitudinally along the center of the shoe.

60 In Fig. 4 I have shown the rod bent to form the two loops F, G, the central strands being upwardly bent to form the key-lug H—H, the extreme ends I—J of the rod meeting on one side of the back.

65 In Fig. 5 I have shown practically the same form of reinforcing back as that shown in Fig. 4, excepting that the two loops K—L are not bent upwardly in the center to form the key-lug.

70 In Fig. 6 I have shown the rod bent to form one wide loop, divided centrally by the strand M into the two loops N—O. Again, in Fig. 7 I have shown the large loop divided by the central loop P.

75 In Fig. 8 I have shown the rod so bent or twisted as to form the three loops Q, R, S, and in Fig. 9, the two loops T—U.

80 Many forms other than those above shown will suggest themselves to those skilled in the art, it being necessary only that the rod be so bent or twisted that the resulting back will practically reinforce the entire back of the shoe and lock or tie together all parts or portions of the shoe which are apt to separate in case it be cracked or broken.

Having fully described my invention, what I claim as new and desire to secure by Letters Patent, is:—

1. A reinforcing back for a brake shoe 90 comprising a rod bent or twisted in several directions, and formed with an integral key-lug, substantially as described.

2. A reinforcing back for a brake shoe 95 comprising a rod bent into a plurality of loops, each strand of said loops having the curvature of the shoe and anchored in the back thereof, substantially as described.

3. A reinforcing back for a brake shoe, comprising a rod bent to form loops and an integral key-lug, substantially as described.

4. A reinforcing back for a brake shoe, consisting of a number of sub-divided loops, and formed from a single rod, substantially as described.

Signed at New York, borough of Man-

hattan, in the county of New York, and State of New York, this 23rd day of January, 1907.

JOSEPH D. GALLAGHER.
